(57) **CLAIM**

The ornamental design for a plumbing fixture, as shown and described.

DESCRIPTION

In a preferred embodiments, the nature of this product is as a plumbing fixture in the form of a water closet, a tank for a water closet, on a base for a water closet.

FIG. 1 is a left, top, front perspective view of a plumbing fixture in the form of a water closet embodying my new design;

FIG. 2 is a top plan view thereof;

FIG. 3 is a left side elevational view thereof, the right side elevational view being a mirror image of the left side shown;

FIG. 4 is a front elevational view thereof;

FIG. 5 is a rear elevational view thereof;

FIG. 6 is a bottom plan view thereof;

FIG. 7 is a left, top, front perspective view of a plumbing fixture in the form of a water closet according to another embodiment of my new design, the top plan view being identical to that of FIG. 2;

FIG. 8 is a left side elevational view thereof, the right side elevational view being a mirror image of the left side shown;

FIG. 9 is a front elevational view thereof;

FIG. 10 is a rear elevational view thereof; and,

FIG. 11 is a bottom plan view thereof.

The broken line representations of openings and/or controls in FIGS. 1-3, and 7, a recess in FIGS. 7-8, and underside and/or interior structure in FIGS. 5-6 and 10-11, are for the purpose of illustration only, and form no part of the claimed design.
